UNITED STATES PATENT OFFICE.

FREDRICK JAMES WEST AND HARRY WILLIAM DARBY, OF WINNIPEG, MANITOBA,
CANADA.

RIVETER.

1,074,396.

Specification of Letters Patent. Patented Sept. 30, 1913.

Application filed July 8, 1912. Serial No. 708,239.

To all whom it may concern:

Be it known that we, FREDRICK JAMES WEST and HARRY WILLIAM DARBY, of the city of Winnipeg, in the Province of Manitoba, Canada, have invented certain new and useful Improvements in Riveters, of which the following is the specification.

The invention relates to an electric riveter and the object of the invention is to provide an efficient electrically operated riveter constructed so that it can be readily assembled and arranged so that the operator can make or break the electric circuit as desired to start or stop the hammer.

15. A further object of the invention is to provide in an instrument of this kind an improved method of taking up the recoil of the hammer.

With the above objects in view the invention consists essentially in the arrangement and construction of parts hereinafter more particularly described and later pointed out in the appended claim.

Figure 1 represents a longitudinal sectional view centrally through the riveter, certain parts being shown in side elevation.

Fig. 2 represents an end view of the riveter.

Fig. 3 represents a vertical cross sectional view through the riveter the section being 30 taken in the plane denoted by the line X—X'

Fig. 1. Fig. 4 represents an enlarged detailed sectional view of the contact plugs and sockets and the parts carrying the same.

In the drawing like characters of reference indicate corresponding parts in each figure.

1 represents an outer cylindrical casing having the ends 2 and 3 thereof screw threaded and the body portion provided 40 with an extending hollow member forming a handle or gripping piece 4.

5 is a cap screw threaded on the end 2 of the casing and 6 is a head piece also screw threaded on the end 3 of the casing. The 45 head piece is fitted with a cross web 7 having an internal threaded opening 8 centrally therein which receives one end of a brass or other such guide tube 9 the other end of which is fitted around the facial projection 5' formed on the inner face of the cap. The head carries also a bearing which is located directly opposite the end of the tube which bearing receives slidably a shank 11 of a hammer 12 having the inner end 55 11' thereof enlarged and slidably mounted

within the end of the tube 9 and the outer end fitted with a permanent collar 11' which bears normally against the head piece. A spring 14 is mounted on the shank between the bearing 10 and the enlargement 11'. 60

15 is a plunger slidably mounted within the tube 9 which plunger is formed from two sections, a central core 16 of steel and an outer covering 17 of soft iron. The core 16 extends beyond one end of the covering 65 and is adapted to hit the head of the hammer when the plunger is reciprocated as later explained.

18 and 19 are two disks in the form of washers located at the ends of the tube or 70 casing.

20 and 21 are insulating tubes having their ends butted against the disks, the tube 20 being passed over the tube 9 while that 75 21 is fitted within the casing.

22, 23, 24 and 25 are magnetic coils of the ordinary form comprising each spools 26 carrying fine insulated wire 27, the ends of the wires being connected electrically to contact rings 28 and 29 located on the ends 80 of the spools. The coils are slipped end to end over the guide tube and appear between the insulating disks 20 and 21. The contact rings 28 and 29 on the adjoining ends of the spools touch so as to establish a 85 continuous electrical connection between the windings. The end of the tube 9 farthest from the hammer is supplied with an internal shoulder 9' against which a steel or other such like metallic disk 30 normally 90 rests being held in this position by the action of a coil spring 31 bearing against the disk and the cap 5.

The end of the handle is fitted with a cap 4' provided with three permanent contact 95 plugs "A," "B" and "C" adapted to plug into suitable contact sockets "E," "F" and "G" connected respectively with the wires "a," "b" and "c." The cups just mentioned are carried by a holder 41 formed 100 from porcelain, ebonite or such like material. The contact plug "A" is connected by a suitable insulated wire "a'" with the contact ring 29 of the magnetic coil 25 and the contact plug "C" is connected by a suitably insulated wire "c" with the contact ring 28 of the magnetic coil 22. The contact plug "B" is connected electrically by a suitably insulated wire "b'" with both contact rings 29 and 28 located on the adjoining ends of the 110

- magnetic coils 23 and 24. A push switch 42 is inserted in the wire b' so that the flow of the current in said wire can be broken when desired. The switch comprises two normally disengaged springs 43 and 44 connected in the wire and carried by the handle, the spring 43 being supplied with a push button 45 which extends outwardly through a suitable slot 46 reserved in the handle.
- 10 The operator will usually close the circuit through the wires b' when he takes the tool up for use as he will grip the handle tightly and in so doing will press the spring 43 in until it makes contact with the spring 44.
- 15 The wires b' and c' are passed to the outside of the casing as a matter of convenience and are inclosed by a split tube 47 carried by the casing. The wires " a ," " b " and " c " of the tool are connected with any suitable form of appliance old in the art which will establish a closed circuit through the wires " a " and " b " and then through the wires " c " and " b ," those circuits being alternately closed and broken as long as the 25 tool is in use. The switch 42 is of course considered as closed at all times when the tool is in use.

The operation of the tool is as follows:— Upon the circuit being closed through the 30 wires " a " and " b " the magnetic coils 24 and 25 are excited through the connecting wires a' and b' with the result that the plunger is drawn into the said coils. Immediately this occurs the circuit through the 35 wires " a " and " b " is broken and a circuit is established through the wires " c " and " b ." This causes the coils 24 and 25 to become inactive while those 22 and 23 are energized with the result that the plunger is 40 drawn into these coils and strikes the head of the hammer delivering a blow on the head of the rivet which is being riveted. The plunger will reciprocate backwardly and forwardly within the tube and deal a succession of blows on the hammer as long as 45 the circuits through " a " " b " and " c " " b " are alternately made and broken. The springs 14 and 31 take up to a certain extent the recoil in the hammer and plunger but 50 this is further accomplished by a magnetic action now explained.

If reference be made to Fig. 1 of the drawings it will be seen that the disk 30 is located normally at the end of the magnetic coil 25 and that said coil and coil 24 when energized will have a constant tendency to draw the disk in the direction indicated by the arrow " h " accordingly when the plunger is drawn back and hits the disk, it will tend to carry

the disk against the magnetic attraction so 60 that the disk in reality will act under the magnetic attraction as a buffer for the plunger on the back stroke. On the forward stroke the hammer of itself has a similar tendency as it is located in such a position 65 that the coils 22 and 23 tend to draw it into the center of said coils when they are excited. This tendency of course is normally overcome by the collar 11² on the outer end of the hammer but immediately the hammer is 70 struck by the plunger and moved in the direction indicated by the arrow " l ," the magnetic attraction above described operated to arrest the plunger.

What we claim as our invention is:—

The combination comprising a brass tube having an internal shoulder formed in one end thereof, a plurality of similar magnetic coils located on the tube and formed each from a spool supplied with a wire winding 80 having the ends of the wire terminating in the opposite ends of the spool, contact rings located on the ends of the spools and connected with the ends of the wires, said rings connecting the coils in series, a casing containing the coils and provided with an extending hollow handle, a cap closing one end of the casing and the end of the tube provided with the shoulder, a metallic disk 90 slideable within the tube and bearing normally against the shoulder, a spiral spring interposed between the cap and the disk, a head piece carried by the opposite ends of the casing and tube, a hammer slidably mounted in the head and provided at the 95 outer end with a collar engaging with the head and at the inner end with an enlargement slidably received within the tube, a spiral spring interposed between the enlargement aforesaid and the head piece, a 100 plunger adapted to reciprocate within the tube and alternately engage with the hammer and the disk, a feed wire passing through the handle and communicating directly with the centrally located pair of 105 contact rings, independent wires passing through the handle and communicating with the contact rings, located on the outer faces of the end coils and push button carried by the handle and inserted in the feed wire, 110 as and for the purpose specified.

Signed at Winnipeg this 26th day of June, 1912.

FREDRICK JAMES WEST.
HARRY WILLIAM DARBY.
